(57) **CLAIM**

The ornamental design for a portable welding clamp attachment device, as shown.

DESCRIPTION

FIG. 1 is a left perspective view of a portable welding clamp attachment device showing my new design.

FIG. 2 is a right side view thereof.

FIG. 3 is a left side view thereof.

FIG. 4 is a top view thereof.

FIG. 5 is a bottom view thereof.

FIG. 6 is a front view thereof.

FIG. 7 is a rear view thereof; and,

FIG. 8 is a right perspective view thereof.

The claimed portable welding clamp attachment device is primarily used to provide a portable device to attach a welding ground clamp or workpiece clamp.

1 Claim, 5 Drawing Sheets

FIG. 1

FIG. 2**FIG. 3**

FIG. 4**FIG. 5**

FIG. 8
